UNITED STATES PATENT OFFICE.

JULIUS A. MAHR, OF MINNEAPOLIS, MINNESOTA, ASSIGNOR TO COZY BABY CARRIAGE CO., OF MINNEAPOLIS, MINNESOTA.

TWIN BABY CARRIAGE.

Application filed January 7, 1924. Serial No. 684,762.

My present invention relates to baby carriages of the type disclosed and broadly claim in my United States Letters Patents Nos. 1,335,122 and 1,432,114, both entitled "Folding baby carriage", issued of date March 30, 1920, and October 17, 1920, respectively, No. 1,363,667, entitled "Baby carrying basket", issued December 28, 1920, and application for Letters Patent, Serial No. 545,100, filed March 20, 1922, and entitled "Baby carriage body". The invention has for its primary object to provide such a carriage with two bodies for holding twin babies.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of the improved baby carriage;

Fig. 2 is a view principally in transverse vertical section taken on the line 2—2 of Fig. 1;

Fig. 3 is an end elevation of the improved baby carriage;

Fig. 4 is a fragmentary detail view showing an improved means for attaching the hood to the body;

Fig. 5 is a detail view principally in section taken on the line 5—5 of Fig. 4;

Fig. 6 is a detail view with some parts sectioned on the line 6—6 of Fig. 5; and

Fig. 7 is a detail view with some parts sectioned on the line 7—7 of Fig. 3 and illustrating one of the body-suspending means attached to the intermediate hook.

Of the parts of the running gear illustrated, it is only necessary to note the reach 8, the posts 9 foldably connected to said

reach by couplings 10, radius rods 11 connected to said couplings and having pivoted stub axles 12 on which are journaled wheels 13, toggle levers 14 for holding said radius rods spread, and locks 15 for securing the reach 8 and posts 9 to the couplings 10 against pivotal movements.

Heads 16, on the upper ends of the posts 9, have upwardly diverging prongs 17, which extend transversely of the carriage and support, at their upper ends, handle bars 18.

Formed on the outer faces of each pair of prongs 17 is a pair of hooks 19, from which twin bodies may be held suspended, and formed with each head 16 is an intermediate hook 20, which projects between said prongs and from which one of said bodies may be held suspended.

The improved baby carriage is provided with two collapsible twin bodies 21, substantially like the body disclosed and broadly claimed in Patent No. 1,363,667 and application S. N. 545,100 heretofore referred to. Each body 21 is made from drilling or other suitable fabric and has, in the marginal edge of its bottom, an endless spreader rim 22 to hold the same in its proper form. Attached to the upper end of the body 21, at the head thereof, is an upwardly inclined extension or web 23 having a marginal hem that holds a U-shaped spreader rim section 24, the ends of which are flattened in vertical planes and transversely apertured to afford elongated seats 25.

A U-shaped spreader rim section 26 is placed in a hem in the upper edge of the body 21, at the foot thereof. The ends of the spreader rim sections 24 and 26 extend toward each other and terminate a considerable distance apart. Attached to the sides of the body 21, between the ends of the spreader rim sections 24 and 26, are buckle-equipped straps 27 for holding a baby in said body.

To suspend the bodies 21 from the hooks 19 and 20, as heretofore referred to, there are provided hanger straps 28 that are passed through gaps 29 in the web 23 and the front end of the body 21, and around the spreader rim sections 24 and 26. Secured in the outer ends of the hanger straps 28 are rings 30 adapted to be interlocked with the hooks 19 to detachably suspend both bodies 21 side by side from the running gear, or said ring may be interlocked with the hooks 20 to detachably suspend only one of said bodies from the running gear.

Pairs of reinforcing straps 31 are extended over the hems, in which the spreader rim sections 24 and 26 are held, and secured by any suitable means, such as rivets, to the web 23 and front end of the body 21, just outward of the gaps 29. Reinforcing straps 32 are extended over the ends of the web 23

and the spreader rim section 24, adjacent to the flattened end portion thereof, and secured to the sides of the body 15 in the same manner as the reinforcing straps 31.

- 5 To independently limit the swinging movement of the body 21 or hold the same against swinging movement, there is provided a transverse bar 33 having at its ends diverging two-part straps 34 attached to the 10 sides of the body 21, and which two-part straps are adjustably connected by buckles 35. This bar, at its intermediate portion, is provided with a depending clamp 36, the jaws of which are adjustably connected by 15 a nut-equipped bolt 37. Said clamp 36 fits around the reach 8 and is frictionally held thereon in the proper position by the nut-equipped bolt 37. The parts of the straps 34 on the bar 32 are also for use in holding the running gear folded and the bodies 21 collapsed and secured to said running gear.

Again referring to the flattened end portions of the rim sections 24, there are provided trunnion-acting bolts 37, the threaded portions of which are flattened and inserted through the seats 25 in such a manner that the heads of said bolts are on the inside of the body 21. The flattened portions of the 30 bolts 37, by the engagement with the elongated seats 25, hold the bolts from turning. Thumb nuts 38 are applied to the bolts 37 and have inwardly tapered body portions. Spring washers 39, on the bolts 37, are arranged to be compressed between the rim section 24 and the thumb nuts 38.

Each body 21 is provided with a hood 40, preferably of the same material as said body and having end and intermediate ribs 41 40 formed from round rods, the ends of which are flattened and apertured to receive the trunnion-acting bolts 37 to pivotally support said ribs, as best shown in Fig. 5. Obviously, by tightening the thumb nuts 38, the 45 ribs 41 will be yieldingly and frictionally held where set under the action of the spring washers 39. Except for the trunnion-acting bolts 37, the hood 40 is entirely free from the body 21 and may be adjusted from 50 a position in which it is folded onto the web 23 to a position in which its front rib 41 engages the upper edge of said body. In the sides of the hood 40, at the tapered lower ends thereof, are eyelets 42 adapted 55 to be inserted onto the tapered bodies of the thumb nuts 38, before they are applied to the bolts 37, and thereby hold the hood 40 in position.

The hood 40 is provided with a detachable hood section 43, of the same material as said hood 40, and the rear edge of which is provided with a web 44 arranged to underlap the web 23 and thereby separately connect the hood extension 43 to the body 60 41 and form a tight joint therebetween.

The hood extension 43 is arranged to adjustably overlap the hood 40 and has, in its forward edge, a hem in which is placed an elastic puckering cord 45 under strain to draw the hood extension 43 onto the hood 70 40. At the lower or pointed ends of the hood extension 43, the elastic cord 45 is extended outward thereof and looped, as at 75 46, to receive the tapered bodies of the thumb nuts 38 and thereby secure the hood extension 43 to the body 21 and anchor said cord.

As previously stated, the hood extension 43 overlaps the hood 40 and, by adjusting the same thereon so that the elastic cord 45 is just forward of one of the ribs 41, said elastic cord will draw the hood extension 43 tightly over the respective rib and form a tight joint between said hood and its extension. 85

From the above description, it is evident that the bodies 21 are independently and detachably suspended from the running gear by the hooks 19 and may be turned end for end, as shown in Fig. 1, or they may be turned so that the two hoods are at the same end of the baby carriage. It is also evident that the bodies 21 may be detached from the hooks 19 and one thereof attached and held suspended from the hooks 20 and thereby equip the baby carriage with a single body. By locating the hooks 20 in line with the posts 7 there is a direct pull on said posts when only a single body is carried by the running gear. 90 95 100

What I claim is:

1. A baby carriage comprising a running gear having a post at each end and independent twin bodies, the posts of the running gear having at their upper ends transversely and outwardly extended members, and attaching means suspending the twin bodies from said members one on each side of the posts in balanced relation and for independent swinging movement. 105 110

2. A baby carriage comprising a running gear, and independent twin bodies carried thereby in balanced arrangement, said running gear having laterally spaced means for detachably holding said bodies side by side and also having intermediate means for detachably holding one of said bodies. 115

3. A baby carriage comprising a running gear including at each end a post having a fork-like head, the prongs of which are connected by a handle bar, laterally spaced fasteners on said prongs, twin bodies detachably held by said fasteners in balanced arrangement, and intermediate fasteners for holding one of said bodies. 120 125

4. A baby carriage comprising a running gear including at each end a post having a fork-like head, the prongs of which are connected by a handle bar, laterally spaced fasteners on said prongs extending out- 130

ward thereof and intermediate fasteners on said heads extending between said prongs, and twin bodies having attaching means engageable with said hooks for holding one or 5 both of said bodies.

5. A baby carriage comprising a running gear, twin bodies carried thereby in balanced arrangement for independent swinging movement, and a cross bar on the running 10 gear having at its ends adjustable diverging straps attached to said bodies for independently holding the same against swinging

movement or for limiting the swinging movement thereof.

6. A baby carriage having a folding running gear including a reach and also having collapsible swinging twin bodies, and a cross bar attached to the reach and having straps at its ends for holding the bodies from swinging and also for holding the running 15 gear folded and the bodies collapsed.

In testimony whereof I affix my signature.

JULIUS A. MAHR.
